UNITED STATES PATENT OFFICE.

LANDY D. EPPERSON, OF MANSFIELD, OHIO.

STEAM-ENGINE REVERSING-GEAR.

SPECIFICATION forming part of Letters Patent No. 714,368, dated November 25, 1902.

Application filed October 24, 1901, Serial No. 79,766. (No model.)

To all whom it may concern:

Be it known that I, LANDY D. EPPERSON, a citizen of the United States, residing at Mansfield, in the county of Richland and State of Ohio, have invented certain new and useful Improvements in Steam-Engine Reversing-Gear; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The special object of the invention is to make a steam-engine reversing-gear in which a single eccentric can be shifted on a spindle in a curve so as to occupy either position of the two eccentrics on a link reverse; secondly, to secure a simple reversing mechanism with only three main parts; thirdly, to make a durable reversing-gear which will wear only when being reversed, and, fourthly, to prevent any slip of the eccentric by the 25 relative construction and arrangement of the parts.

Figure 1 of the drawings is a plan view of my invention with the parts in conjunction as used; Fig. 2, an enlarged view of the eccentric with its shell and spindle; and Figs. 3 and 4, end views, respectively, of the spindle-bearing piece and the shaft-sleeve which is operated by the lever. Fig. 5 is a vertical side elevation; and Fig. 6 is an end view, the 35 shaft being in cross-section.

In the drawings, A represents the eccentric-shell with its diagonal slot α and its spin-

dle a' . This shell is secured adjustably to the engine-shaft C by means of the piece D, which has a bearing d' for the spindle a' and 40 the collar d , held to shaft by a set-screw d^2 .

E is the sliding sleeve, moved back and forth by the reversing-lever, whose collar fits in the annular groove e , said lever not being shown. By my swinging eccentric I can 45 place it in exactly the same position as with the two eccentrics in a link-motion.

In reversing gears which shift straight across the shaft the work is not properly done at the valve, while there is more resistance 50 to the action of the reversing-lever than is necessary. The sliding sleeve E carries a stud e' , which may carry a friction-roller to work in the slot a of the eccentric as said sleeve is slid on the shaft C in a straight 55 line, while the eccentric turns with its spindle a' in the bearing d' , so as to move across the engine-shaft. The sleeve E has a screw e^2 , which passes therethrough and works in a longitudinally-straight slot of the shaft to 60 prevent said sleeve from turning.

What I claim as new is—

A swinging eccentric with a diagonal slot α and a spindle a' opposite or nearly opposite thereto, a fixed collar d with a bearing d' , 65 and a sliding sleeve E in combination with an engine-shaft, to form a reversing-gear as shown and described.

In testimony whereof I affix my signature in presence of two witnesses.

LANDY D. EPPERSON.
